UNITED STATES PATENT OFFICE.

EDWARD E. JOY, OF DEXTER, KANSAS.

CAR-COUPING.

SPECIFICATION forming part of Letters Patent No. 603,062, dated April 26, 1898.

Application filed August 28, 1897. Serial No. 649,879. (No model.)

To all whom it may concern:

Be it known that I, EDWARD E. JOY, a citizen of the United States, residing at Dexter, in the county of Cowley and State of Kansas, have invented certain new and useful Improvements in Safety Car-Couplings; and I do hereby declare the following to be a full, clear, and exact description of the invention, such as will enable others skilled in the art to which it appertains to make and use the same.

My invention relates to novel and useful improvements in car-couplers; and it has for its object, primarily, to provide a car-coupler that will be simple in construction, durable, and efficient in operation.

Further, the invention contemplates the provision of a car-coupler that will be automatic in its coupling action, thus avoiding the danger to human life where the cars are coupled by the usual pin and link.

The invention consists in the novel features of construction and combination of parts hereinafter more particularly set forth and claimed.

In the accompanying drawings, forming a part of this specification, Figure 1 is a perspective view of the front portion of the car with my improved coupler applied thereto. Fig. 2 is a longitudinal central section of one of the couplers, showing the same in uncoupled position; and Fig. 3 is a similar view of the coupler and its companion in coupled position.

Referring to the drawings, the numeral 1 indicates the frame, comprising a top bar 2 and a bottom bar 3, connected together at their rear ends by a member 4 and braced at suitable points by members 5.

The numeral 5' indicates the draw-bar, 40 which is provided near its rear end with two elongated slots 6, through which extend two studs 7, having their ends secured to the bars 2 and 3, said studs being for the obvious purpose of limiting the longitudinal movement 45 of the draw-bar. Interposed between the member 4 and the rear end of the draw-bar is a spiral spring 8, which keeps the draw-bar normally forced forward. The front end of the draw-bar is bifurcated to form two arms 9 and 10 and a recess 11, which recess is adapted to receive one of the bifurcated ends of

the companion coupler when the couplers are in coupled position or as shown in Fig. 3.

The numeral 12 designates two slots provided at the upper and lower ends of the arms 5 9 and 10, which slots are for the reception of the coupling-pin 13, which is kept normally forced downward by a spring 14, suitably secured to the top of the draw-bar, near the forward end thereof. Said coupling-pin is maintained in an elevated position when it is desired to couple the cars by a sliding member 15, having the curved forward end 16, adapted to enter a notch 17 in the coupling-pin. Said member is guided in its longitudinal 60 movement by staples or keepers 18, and is provided at its rear end with a short vertical arm 19, which is in engagement with the spiral spring 19', suitably supported upon the upper side of the draw-bar, said spring 70 being for the obvious purpose of keeping the forward end of said member normally in engagement with the coupling-pin. Pivotedly mounted between the two ears 20 upon the upper side of the draw-bar is a lever 21, having its forward end pivotally connected with the coupling-pin, said lever being adapted to be rocked to elevate the coupling-pin and maintain the same in position for coupling. 75

The bifurcated arms are provided with registering slots 12 for the reception of the coupling-pin of the companion coupler when the couplers are brought together in position for coupling.

I preferably interpose between the draw-bar and the frame, at the upper and lower sides of the draw-bar, a plurality of leaf or other springs for the purpose of maintaining the draw-bar in its proper relative position to the frame. 85

Having described the mechanism wherein the invention lies, I will now proceed to describe its operation.

Assuming the coupling to be in elevated position and maintained in such position by the 95 spring-actuated sliding members described, the couplers are brought together until the slots in the respective draw-bars register and the coupling-pins are in position to be extended through the slots near the rear ends 100 of the recess. At this moment the impact of the draw-bars will cause each to move rear-

wardly, and in so doing it will bring the short vertical arms 19 in engagement with the forward edges of the respective frames, causing the sliding members to move forwardly and release the coupling-pins and permit them to simultaneously pass through the slots in the respective draw-bars.

Having thus described my invention, what I claim as new, and desire to secure by Letters Patent, is—

1. A car-coupler, comprising a longitudinally-yielding draw-bar and a suitable frame for said bar, said draw-bar having its forward end bifurcated and provided with a slot in its forward end, a spring-pressed coupling-pin adapted to be passed through said slot, a lever pivotally supported from the draw-bar and adapted to be rocked to elevate the coupling-pin to uncouple the cars, a sliding spring-actuated member adapted to engage the pin and keep the same normally elevated, said member being provided at its rear end with an arm adapted to engage the frame when the cars come together, to release the pin and permit the same to be forced downwardly through the slots in the companion coupler, said draw-bar being also provided with the registering slots adapted to receive the coupling-pin of the companion coupler, and means for keeping the draw-bar normally forced upward, substantially as described.

2. A car-coupler, comprising a rearwardly yielding draw-bar, a suitable frame for said draw-bar having studs passing through elongated slots in the rear portion thereof to limit the horizontal movement of the draw-bar, said draw-bar being provided with bifurcated forward end having vertical slots therein for the passage of the coupling-pin carried by the draw-bar, and the coupling-pin carried by the companion coupler, a spring-pressed coupling-pin in the slot in the forward end of the draw-bar, a lever pivoted upon the draw-bar and having its forward end connected with the coupling-pin, whereby the same is elevated, a spring-actuated sliding arm having its forward end in engagement with the coupling-pin, whereby the same is maintained in elevated position, said member having an arm at its rear end adapted to engage the draw-bar frame when the cars are brought together and thereby permit the coupling-pin to be forced downwardly, substantially as described.

In testimony whereof I have signed this specification in the presence of two subscribing witnesses.

EDWARD E. JOY.
